UNITED STATES PATENT OFFICE.

HYMEN L. LIPMAN, OF PHILADELPHIA, PENNSYLVANIA.

DESIGN FOR AN EYELETING-MACHINE.

SPECIFICATION forming part of Design No. 13,292, dated September 12, 1882.

Application filed August 10, 1882. Term of patent 7 years.

To all whom it may concern:

Be it known that I, HYMEN L. LIPMAN, a citizen of the United States, and a resident of Philadelphia, Pennsylvania, have invented or 5 produced a new and original Design for an Eyeletting-Machine, of which the following is a specification.

My design for an eyelet-machine is fully shown in the accompanying drawing, which 10 represents a perspective view of the machine.

A is the base of the machine, from the rear of which rises a curved standard, B, and from the latter projects a bar, D, which is expanded at the front end into a bearing, E. From the 15 standard B rises another curved standard, F, terminating in a bearing, G. The two bearings are connected by a bar, H, on which is a representation of a bearded face. At the top

of the bar H are bearings for the two levers J J, which operate the punch K and eyeletting-plunger L. Between the bearings E and G are sleeves M, which surround the punch and eyelet-plunger, and on the base A are the punch-block N and eyelet block P.

I claim—

The design for an eyeletting-machine, substantially as described, and as shown in and by the accompanying drawing.

In testimony whereof I have signed my name to this specification in the presence of two subscribing witnesses.

HYMEN L. LIPMAN.

Witnesses:

HARRY DRURY,
HARRY SMITH.
